[57] **CLAIM**

The ornamental design for a dispenser for air treating material, as shown and described.

DESCRIPTION

FIG. 1 is a top and side perspective view of a dispenser for air treating material showing our new design in closed position;

FIG. 2 is a front elevation view thereof;

FIG. 3 is a top plan view thereof;

FIG. 4 is a side elevation view thereof, the opposite side being a mirror image of that shown;

FIG. 5 is a bottom plan view thereof; and

FIG. 6 is a side elevation view of a dispenser for air treating material in the open position, the opposite side being a mirror image of that shown.
